P.O. Box 1174, Studio City, Calif. 91604

Filed July 25, 1968, Ser. No. 12,892

Term of patent 14 years

U.S. Cl. D83—1
Int. Cl. D24—02; D23—02

FIG. 1 is a perspective view of a hydrotherapy pool showing my new invention;

FIG. 2 is an end elevation as seen from the right of FIG. 1;

FIG. 3 is an end elevation as seen from the left of FIG. 1;

FIG. 4 is a top plan view thereof; and

FIG. 5 is a side elevation of a modified embodiment of the hydrotherapy pool illustrated in FIG. 1, wherein the difference resides in the omission of the lowermost well, as best illustrated in side elevation.

I claim:

The ornamental design for a hydrotherapy pool, substantially as shown and described.
